TELEPHONE SYSTEM

Horace Edgar Humphries, London, England, assignor to Siemens Brothers & Company Limited, London, England

Application January 27, 1932, Serial No. 589,221
In Great Britain January 30, 1931

4 Claims. (Cl. 179—16)

This invention relates to automatic and semi-automatic telephone systems and more particularly to improved impulse repeating arrangements for use in connection with inter office working.

In certain known arrangements impulse repetition is effected over a split circuit in which the impulses are repeated from the incoming to the outgoing side of a transmission bridge by means of an impulse accepting relay in the incoming side having contacts included in a loop circuit in the outgoing side of the circuit. The outgoing side of the circuit usually includes a comparatively high impedance, such as an answering supervisory relay or impedance coils, or both, the high impedance being shunted out of the impulsive circuit by means of contacts of a slow acting relay operated by the first impulse of an impulse train. The first impulse break however, is usually repeated before the slow acting relay operates to shunt the high impedance and as a consequence the energy stored in the impedance dissipates itself through the impulse accepting relay and may cause its false operation and the consequent clipping or mutilation of the first impulse. Also in certain known arrangements the impulse repeating contacts are shunted by contacts of an answering supervisory relay to avoid the outgoing loop being momentarily opened when the direction of current in the trunk line wires is reversed in response to the reply of the called subscriber. Further, when two remote circuits are tied together, such as two tandem repeaters, and the impulse repeating contacts in the first are shunted in the manner described, there is a possibility of the called circuit being picked up before it has released since the called circuit remains held during the release of its release relay at the time the originating circuit is free.

As regards impulse repetition, according to the main feature of the present invention a shunt path of lower impedance than the path offered through the impulse accepting relay is connected to the impedance at the commencement of the first impulse of an impulse train and before or substantially at the same time as the outgoing loop circuit to the distant exchange is opened. Therefore upon the opening of the loop to the break portion of the first impulse the energy stored in the impedance will dissipate itself through the low impedance path, the impulse accepting relay being unaffected.

The low impedance path may be closed over a contact set of the impulse accepting relay, the

contacts being of the make before break type and on relapsing connect the shunt circuit before breaking the loop. An ordinary break before make type of contact may suffice.

The shunt circuit may comprise a short circuit, or a simple non-inductive resistance may be used so that the dissipation of the stored energy occurs gradually which prevents sparking at the impulse repeating contacts.

By the use of make before break impulse repeating contacts, the trouble caused through the possible relapse of the impulse accepting relay on the reversal of line conditions when the called party replies is overcome as the contacts would not open to a momentary flick of the impulse accepting relay or if they do open the answering supervisory relay is slow to release by reason of the shunt. Similarly by the omission of shunting contacts across the impulse repeating contacts the calling and distant circuits are released almost simultaneously thus avoiding the possibility of one circuit testing free while the other is held.

The accompanying drawing illustrates by way of example the application of the invention to a simple impulse repeater employing booster battery metering and in which the incoming and outgoing sides are split by condensers, the incoming side being fed with battery over the impulse accepting relay.

The positive, negative and private wires incoming from a selector are marked +, —, and P, the positive and negative wires being connected via condensers to outgoing wires a and b.

The impulse accepting relay A is bridged across the + and — wires via make before break change over contacts of a relay DD which is a relief relay to the shunt field answering supervisory relay D bridged across the wires a and b in series with inductance coil I. A make before break change over contact of relay A is included in the wire b, the contact when normal connecting a resistance R across the local exchange side of the wires a and b. Relay B is a usual slow to release release relay and relay C is operative in response to the first impulse of a train to connect a clean impulsive loop to the distant office. Relay J is slow in operation and operated on the seizure of the circuit to prepare for the application of metering conditions. Relays B, C and J being slow to release remain operated throughout trains of impulses.

Considering the circuit in detail, the free condition of the circuit is characterized by an open wire P, and when a searching selector seizes the

- circuit relay A operates to a loop condition over the + and - wires. At contact a_1 a circuit is closed for relay J via contact b_4 , and at contact a_2 the impulsing loop to the junction is prepared.
- 5 Relay J operates and prepares a locking circuit for itself at contact j_1 . Relay B is operated over contacts j_2 and a_1 , and at contact j_3 an earth is connected to the wire P to busy the repeater against other searching selectors and hold the connection back to the calling party.
- 10 At contact b_1 earth is prepared for connection to the wire P to busy the repeater when relay J releases, whilst at contact b_2 an energizing circuit is closed for the polarizing coil of shunt field relay D. Contact b_3 prepares the circuit for relay C, and contact b_4 closes a locking circuit for relay B independent of contact j_2 . At contact b_5 the locking circuit for relay J is closed, and at contact b_6 the loop to the distant exchange is closed over inductance coil I and upper coil of relay D which relay however does not operate as the currents through its coils are not in the requisite directions to allow the relay to operate.
- 15 The circuit is now in a condition to receive impulses.
- 20 At the break portion of the first impulse relay A relapses and at contact a_1 operates relay C. At contact a_2 before relay D and inductance coil I are short circuited by the operation of relay C a shunt circuit is connected across the conductors a and b over resistance R, the eventual breaking of the contact transmitting the break portion of the first impulse over the outgoing junction.
- 25 On the breaking of the impulsing loop at contact a_2 two circuits are made for the dissipation of the energy stored in inductance coil I and upper coil of relay D, one circuit being through the resistance R and the other through the splitting condensers and relay A. The former circuit is of much lower impedance than the latter with a consequence that the energy will mainly dissipate itself through this circuit leaving relay A unaffected.
- 30 Shortly after contact a_1 relapses relay C operates and at contact c_2 closes a short circuit across inductance coil I and relay D, and prepares a clean impulsing loop to the junction.
- 35 At contact c_1 the relapse of relays J and B is guarded against by preparing to earth wire P.
- The remaining impulses of the train are transmitted to the outgoing junction over contacts a_2 , c_2 and b_6 , and after the train has ceased and relay A is held permanently, relay C releases to disconnect the non-inductive loop at contact c_2 and disconnect the guarding earth from wire P, at contact c_1 .
- 40 When the called party answers the direction of current over the a and b wires is reversed and relay D operates. At contact d_1 a circuit is closed for relay DD which relay at contacts dd_1 and dd_2 reverses the battery connections to the + and - wires. At contact dd_3 the busy earth is disconnected and a booster battery connected to the wire P over the wire BB to cause the operation of the calling party's meter.
- 45 The circuit for relay J is broken at contact dd_4 , but this relay being slow to release does not release immediately but allows ample time for the metering signal to be passed over wire P. However on the relapse of relay J the booster battery is removed and an earth over contact b_1 connected. At contacts j_1 and j_2 the locking
- 50 circuit for relay J and the temporary locking circuit for relay B, respectively are broken.
- 55 During the change over of contacts dd_1 and dd_2 on the operation of relay D and DD it is probable that a momentary release of relay A will occur, the release however will generally be of such short duration that the contacts a_2 , being make before break, will not relapse to break the outgoing loop. If the contacts a_2 do fully relapse the resistance R will be placed across the upper coil of relay D, in effect making this relay slow to release, the relay holding up until relay A re-operates. The momentary opening of the loop to the junction will not affect the apparatus at the distant end as the release relay in this circuit will remain operated during the short opening of the line.
- 60 It will be clearly seen that if the shunt circuit is not provided the only path through which the energy may dissipate is through the splitting condensers and relay A which relay may operate and clip the impulse.
- 65 When the calling party releases relay A relapses opening the circuit of relay B at contact a_1 , relay B releases in turn opening the circuit for relays D and DD. Almost simultaneously with the restoration of contact a_1 , a_2 restores and disconnects the loop to the distant exchange. Thus the release relays at the home and distant exchanges commence to restore almost simultaneously, the release of both circuits occurring almost at the same time thus neither circuit will be held whilst the other is free.
- 70 The contact a_2 may be of the ordinary break before make change over type, but the characteristics of the contact must be such that the break on relapse occurs very late and just prior to the make, so that the discharge from the impedance does not flow for a sufficient period before the shunt R is connected by the make to cause the 100 operation of relay A. Further the resistance R is not necessary as a simple short circuit will suffice, but however the inclusion of a resistance in the shunt circuit is preferred as this prevents 105 sparking across the impulse repeating contacts when relay A relapses.
- 75 The contact a_2 may be of the ordinary break before make change over type, but the characteristics of the contact must be such that the break on relapse occurs very late and just prior to the make, so that the discharge from the impedance does not flow for a sufficient period before the shunt R is connected by the make to cause the 110 operation of relay A. Further the resistance R is not necessary as a simple short circuit will suffice, but however the inclusion of a resistance in the shunt circuit is preferred as this prevents 115 sparking across the impulse repeating contacts when relay A relapses.
- 80 What I claim as new and desire to secure by Letters Patent is:
1. In an impulse repeater, a line relay in bridge of the line incoming to said repeater, a supervisory relay in bridge of the line on the outgoing side, contacts on the line relay for closing the outgoing line when the line relay energizes, and contacts on the line relay closed by de-energization thereof for shunting the supervisory 120 relay.
- 85 2. In an impulse repeater, a line relay in bridge of the incoming line, an impedance in bridge of the outgoing line, contacts on the line relay for closing the outgoing line circuit through said impedance, thereby magnetizing the same, and means operated by the line relay on deenergizing to break said outgoing line circuit which is effective to dissipate the energy stored in the said 130 impedance and thus prevent such energy from interfering with the proper operation of the line relay.
- 90 3. In an impulse repeater, a line relay in bridge of the incoming line, an impedance in bridge of the outgoing line, contacts on the line relay for closing the outgoing line in series with the said impedance when the line relay is energized, a relay for shunting said impedance, a circuit closed through said shunting relay by deenergization of the line relay responsive to in- 140
- 95 145
- 100 150

terruptions of the incoming line circuit, and contacts on said line relay closed by deenergization thereof for shunting said impedance before the said shunting relay has had time to operate.

5 4. In an impulse repeater, a line relay controlled over the incoming line, contacts on the line relay for closing the outgoing line circuit, said contacts for opening the outgoing line cir-

cuit when the line relay deenergizes, an impedance in the outgoing line circuit at the repeater, and means for shunting said impedance upon de-energization of the line relay, said means being effective before the outgoing line circuit is 80 opened.
